IMPROVED VISE.

EMMETT COON, OF KALAMAZOO, MICHIGAN.

Letters Patent No. 60,144, dated December 4, 1866.

SPECIFICATION.

TO ALL WHOM IT MAY CONCERN:

Be it known that I, EMMETT COON, of Kalamazoo, in the county of Kalamazoo, and State of Michigan, have invented a new and useful improvement in Vises; and I do hereby declare that the following is a full, clear, and exact description of the construction and operation of the same, reference being had to the accompanying drawings, and to the letters of reference marked thereon. Like letters refer to corresponding parts in each figure.

Figure 1 is a perspective view of my vise, showing the proper arrangement of all the parts.

Figure 2 is a view of the inner surface of a jaw and die.

Figure 3 is a plan of a die inverted.

Figure 4 represents a bevelled die or block with a horn attached.

Figure 5 represents a die or block with two bevels on the upper surface.

A, fig. 1, is an upright standard resting on a pedestal B. From the pedestal a slot extends upward in said standard. C represents a curved lever attached to a bolt in the slot of the standard A, said bolt constituting the fulcrum. The upper ends of the standard A and lever C correspond in shape and dimensions, and constitute the jaws of the vise. At the lower end of the lever C is placed the spring D, the upper end of which rests against the short arm of the lever C below the fulcrum, and the lower end is secured in any convenient manner to the lower end of the standard A, or to the pedestal B. The said spring serves to keep the short arm of the lever D pressed into the slot in the standard A, and thus keeps the jaws of the vise open when they are not brought together, as hereinafter explained. E represents an elbow friction-lever, the fulcrum of which is on a bolt passing through the slot in the standard A. The short arm of said lever rests against the short arm of the lever C, and the long arm projects outward, as shown in fig. 1. By forcing down the long arm of the lever E the jaws are brought together, and when the pressure is removed the spring D forces them apart. To the jaws of the vise I attach metallic slip dies F F, on the under surface of which are bevelled keys e e, which fit into corresponding grooves in the jaws, forming a dovetail attachment. The grooves in which the dies are placed contract in breadth as they approach the outside of the jaws. The upper surface of the dies may be constructed of any desirable form; and for making nails, bolts, &c., I use dies with cavities b b, in the inner edge thereof, of any desirable form or size. When the jaws of the vise are brought together these cavities form holes, into which the heated iron is driven; and in this way nails, bolts, &c., corresponding in shape and size to said holes, are made. When it is desired, I attach a horn to the dies, as represented at d, fig. 4. I also use the bevelled dies or blocks figs. 4 and 5, one being lower than the other, for the purpose of forming horse-shoe calks. Fig. 5 has an inward bevel, represented at n, making it lower than the die, fig. 4, and thus forming a recess for forming the calks.

Among the advantages of having a vise constructed with detachable, or slip dies, and dies with cavities, are the following, viz:

1. When the dies become battered and defaced by usage they may be dressed over very easily or replaced by new ones, whereas when the ordinary vise becomes defaced it is repaired with considerable difficulty; and unless made of wrought iron or steel it cannot be repaired at all, and thus becomes useless.

2. By means of the detachable slip dies I can have a vise of any form desired, for any kind of work for which a vise is used, by simply having different-formed dies.

3. All the parts, except the dies and spring of my vise, may be made of cast iron, thus reducing the expense, but still being as good as if all the parts were made of wrought iron and steel, as it is only the jaws of a vise that are liable to become impaired by usage.

4. By the use of dies with cavities, nails, bolts, &c., may be headed at one heating, and in about one-half the time required to do the work by the old process of using a heading tool, which requires a number of heatings.

What I claim as new in my invention, and desire to secure by Letters Patent, is—

1. The adjustable dies F F, with cavities b b, and keys e e, as and for the purpose set forth.

2. The adjustable dies, figs. 4 and 5, made with the bevel n, horn d, and keys e e, when used in combination with a vise.

EMMETT COON.
